UNITED STATES PATENT OFFICE

CARL O. FEDDERN, OF PHILADELPHIA, PENNSYLVANIA, ASSIGNOR TO GLOBE TICKET COMPANY, OF PHILADELPHIA, PENNSYLVANIA, A CORPORATION OF PENNSYLVANIA

TICKET HOLDER

Application filed September 12, 1928. Serial No. 305,602.

This invention relates to a ticket holder arranged to receive a pad of tickets or the like and provided with means whereby the tickets may be torn in a predetermined manner from the pad whereby data relating to time of issuance, destination, etc., may be readily indicated on the severed ticket or the stub.

The broad object of the present invention is the provision of an improved holder of the character described which is of simple and rugged construction, capable of ready adjustment, and which will render the insertion and issuance of tickets rapid and easy. The more specific objects relate to the provisions of elements designed to cooperate to produce these results and will become more apparent upon study of the following description in connection with the accompanying drawing, in which:

Fig. 1 is a plan view, partly in section, of the improved holder.

Fig. 2 is a side elevation of the same.

Fig. 3 is a longitudinal central section of the holder.

Fig. 4 is a section on line 4—4 of Fig. 2.

Fig. 5 is a section on line 5—5 of Fig. 3.

In the preferred embodiment disclosed, the holder comprises a base 2 which is adapted to be suitably mounted in a convenient position in a vehicle or ticket office, or the like, and which is provided with a flap top 4. Slidably mounted on top 4 is a slide 6 which is maintained in properly guided position for longitudinal sliding by means of lugs or pins projecting downwardly through elongated slots 8 formed in top 4 of the base. Secured beneath the forward end of slide 6 and therewith is a plate 10 which extends through a slot in the front of the base 2 and underneath top 4 to prevent rise of the forward end of the slide. The slide is maintained in a forward position by means of a tension spring 12 secured at its ends to pins 14 and 16, respectively connected to slide 6 and top 4. Pin 14 extends downwardly through an elongated slot in top 4 and forward movement of slide 6 is limited by means of a stop 17 extending downwardly through this same

slot, coming into engagement with the forward end thereof, as shown in Fig. 3.

A clamping plate 18 is mounted in parallel spaced relationship with slide 6, as indicated in Fig. 3, and is provided with downwardly extending portions and a pin 20 which project downwardly through the slide and clamping plate 18 for vertical sliding movement with respect thereto. To the lower end of pin 20 is pivoted a cam 22 provided, as shown in Fig. 3, with an eccentric cam face arranged to engage the under side of slide 6. This cam may be moved by means of a lever 24 secured thereto which, when moved to the horizontal position shown in Fig. 1, brings the more eccentric portion of cam 22 into engagement with slide 6, thereby pulling plate 18 downwardly against the tension of a leaf spring 26 which normally tends to raise plate 18. Prongs 28 are provided on the front of the plate 18 and are arranged to penetrate and engage the stub A of a pad of tickets placed in the holder. Upon engagement of the pad upon prongs 28, cam 22 may be properly positioned to clamp the stub end of the pad between plate 18 and slide 6. Upstanding guides 29 are provided at the sides of slide 6 to properly position the side edges of the pad.

Rotatably mounted transversely in the front of the frame is a shaft 30 to which is rigidly secured a guide rod 32 extending rearwardly. To the rear end of guide rod 32 is secured a bracket arm 34 extending transversely to the opposite side of the holder. Pivotally mounted in the opposite ends of shaft 30 and bracket 34 is a rod 36 provided at its forward end with a knurled head which may be grasped by an operator to turn the same. The rearward portion 40 of rod 36 is threaded.

A casing 42 of the configuration shown in Figs. 1 and 3 is provided with downwardly extending lugs 44 and 46 which are bored to slidably receive rods 32 and 36. Mounted in a cut-away portion of lug 46 on a pin 48 is a lever 50, arranged for manual manipulation, the lower end of which is provided with teeth 52 engageable with the threads 40 on

rod 36. The threaded portion of lever 50 is pressed into engagement with screw 40 by means of a compression spring 54 arranged in the top of the casing.

It will be observed from the above that by manual movement of lever 50 to remove teeth 52 from engagement with the screw, casing 42 is rendered free to be moved longitudinally along rods 32 and 36. This movement provides a rough adjustment for casing 42. A fine adjustment may be obtained by permitting teeth 52 to be yieldingly pressed against screw 40, when a rotary movement imparted to rod 36 through knurled head 38 will produce a slow and fine longitudinal movement of the casing.

The front edge of the casing is provided with a severing edge 56 arranged to rest on the pad of tickets, or the like, and which will determine a line along which tearing will take place when a ticket is removed. One or more indentation forming fingers 58 may be adjustably mounted on the front of casing 42 as, for example, in a slot 60 formed therein.

The forward end of casing 42 is curved rearwardly as shown at 62, forming a type of knife edge. By reason of this edge 62, after a ticket is severed along edge 56 slide 6 may be manually moved rearwardly by a push upon the forward edge thereof, bringing the free edge of the stub of the severed ticket to the rear of knife 62. The subsequent return of the slide to forward position will cause the riding of the free end of the stub up and over knife 62 with its consequent retention in the casing.

Supposing that it is desirable to limit the use of tickets to half hour intervals, the tickets may be provided adjacent the stub ends with a plurality of columns C containing blocks marked with hours and half hours as shown. Obviously, any other data may be similarly indicated and any number of columns may be provided although for simplicity only two columns, one containing hours and the other half hours, are described. If it is desired to indicate the hours on the severed tickets, finger 58 may be positioned as indicated in Fig. 1, while if half hours are to be indicated, the finger is correspondingly moved over the blocks in which the half hours are marked. In positioning a pad for use, casing 42, together with guide rods 32 and 36, may be rotated about shaft 30, thus clearing the upper surface of slide 6. The pad is then positioned on prongs 28 and clamped between plate 18 and the upper surface of the slide. Casing 42 may now be brought down upon the pad and longitudinally adjusted either by a rough or fine adjustment, or both, to a position with severing edge 56 above the line adjacent the time or other data which it is desired to indicate. In issuing the tickets, the operator merely grasps the free end B

of a ticket and tears it along edge 56. During this tearing, finger 58 will provide the proper indentation in the torn edge while a projection will be provided on the stub corresponding thereto. Subsequently to severing a ticket, the operator will push slide 6 rearwardly against the tension of spring 12 and then free the slide so as to be brought forwardly by the spring. This will result in carrying the free edge of the stub rearwardly of knife 62 and its subsequent retention within casing 42.

Since, in their broad aspect, various features of the present device are incorporated in the device shown in my application Ser. No. 305,601, filed September 12, 1928, reference is made to that application for claim covering the common features of the two modifications.

What I claim and desire to protect by Letters Patent is:

1. A ticket holder comprising a base, means for holding a pad of tickets mounted on the base, an adjustable severing edge supported by the base over the pad, and means for adjusting said severing edge over the surface of a ticket comprising a rotatable screw carried by the base, and means carried by the severing edge and operatively engaging the screw whereby rotation of the screw imparts movement to the edge, said last named means being disengageable from the screw.

2. A ticket holder comprising a base, a slide mounted on the base and adapted to hold a pad of tickets, and a severing edge supported by the base over the pad, and means for yieldingly urging said slide in a direction to project the free edges of the tickets forwardly of the edge, said slide being movable rearwardly to carry the free edge of a stub of a severed ticket rearwardly of the edge.

3. A ticket holder comprising a base, a slide mounted on the base and adapted to hold a pad of tickets, a severing edge supported by the base over the pad, means for yieldingly urging said slide in a direction to project the free edges of the tickets forwardly of the edge, said slide being movable rearwardly to carry the free edge of a stub of a severed ticket rearwardly of the edge, and means at the rear of said edge for lifting the free edge of a stub from a ticket lying therebelow during a subsequent forward movement of the slide.

In testimony of which invention, I have hereunto set my hand at Philadelphia, Pennsylvania, on this 10th day of September, 1928.

CARL O. FEDDERN. 125
